FIG.1.

FIG.2.

FIG.3.

FIG.4.

Inventor
Conrad Dressler
By his Attorney
Geo. W. Scoville

UNITED STATES PATENT OFFICE.

CONRAD DRESSLER, OF MARLOW, ENGLAND.

TUNNEL-KILN.

1,225,318.

Specification of Letters Patent. Patented May 8, 1917.

Application filed May 24, 1916. Serial No. 99,535.

To all whom it may concern:

Be it known that I, CONRAD DRESSLER, a subject of the King of Great Britain and Ireland, residing at Marlow, in the county 5 of Bucks, England, have invented certain new and useful Improvements in Tunnel-Kilns, of which the following is a specification.

My invention relates to tunnel kilns of the 10 type described in my prior Patents Nos. 1,023,628 dated April 16, 1912 and 1,116,036 dated Nov. 3, 1914. In the construction described in such patents, the combustion chambers are arranged longitudinally along 15 each side of the floor of the tunnel oven, and adapted to be fed with a combustible gas at one point, the products of combustion finding egress through a chimney at the opposite end. With such a construction, the 20 temperature is highest at the point of introduction of the combustible gas, and lowest at the point of egress of the gas. For kilns where a high temperature at the inlet end and a lower temperature at the outlet end is 25 desirable, such construction has been found efficient. For kilns where a moderate temperature at the inlet end, a high temperature at the center and a lower temperature at the outlet end is desirable, such construction has 30 been found faulty.

The purpose of my present invention, therefore, is a construction in which the temperature at different points along the length of the kiln may be regulated, as desired, and this regulation is accomplished 35 by connecting the source of combustible gas to the combustion chambers at different portions of their length, and the provision of valves whereby the amount of combustible 40 gas and air introduced may be varied as desired.

The accompanying drawings will serve to illustrate my invention, in which, Figure 1 is a horizontal section approximately on 45 the line I—I of Fig. 2. Fig. 2 is a sectional elevation, the section being approximately on the line II—II of Fig. 1. Fig. 3 is a transverse section on the line III—III of Fig. 2. Fig. 4 is a detailed sectional view 50 on the line IV—IV of Fig. 1.

Referring to the drawings: 1 represents the combustion chambers arranged longitudinally of the hearth of the inclosing chamber 2. The combustion chambers are 55 divided into sections 3, and interposed between the sections are sleeves 4, which receive the ends of adjacent sections 3, and

allow them to expand and contract therein. Connected to the sleeves 4 at one side, are tubes 5. The tubes are located in the opposite side walls of the inclosing chamber 2. Projecting into the tubes 5 are burners 6, connected at the rear end to a gas delivery pipe 7. The burners 6 are of the usual type, provided with air controlling dampers 8. 60 The outer ends of tubes 5 are situated in a sleeve 9, located in the outer surface of the wall of the inclosing chamber 2. The tubes 5 are adapted to be freely movable, to compensate for expansion and contraction in 65 the sleeves 4 and 9. The gas supplied to the burners 6, is controlled by valves 10. Located at the forward end of the chambers 1 (i. e., the entrance end of the kiln) are furnaces 11, as shown in Fig. 4. These furnaces are of the usual construction. In 70 place of the furnaces, gas and air burners may be used, as disclosed in my prior Patent No. 1,023,628.

The combustion chambers 1 are connected 75 at their rear end to a chimney stack 12, at the delivery end of the kiln. Located within the bottom of the inclosing chamber 2, is a trackway 13, on which is mounted a truck 14 to carry the articles 15 to be treated in 80 the kiln.

The operation of the kiln is as follows: Under ordinary conditions, the combustion chambers are heated by means of heat units 85 derived from the fuel in the furnaces 11, or as before stated, from the gas and air burners which take the place of the furnaces. The heat derived from the combustion of fuel in the furnaces 11, is supplemented by 90 the heat derived from the combustion of gas and air at any of the burners 6. In treating 95 various articles, it is desirable to have the temperature at the entrance end of the inclosing chamber 2, comparatively moderate. This temperature, in such case, is derived 100 from the furnaces 11, and to have the temperature at the center of the furnace high—sufficiently high to vitrify the articles treated—this temperature is derived from the furnaces 11, added to by the temperature 105 at the burners 6 at the center of the furnace. The temperature at the rear end of the inclosing chamber will be that due to the temperature derived from the furnace 11, as modified by the loss of temperature along the length of the furnace, or that due to one or more of the burners 6 when in operation, as modified by the length of the furnace, or that due to the temperature of 110

the furnace 11 plus that of the burners 6, which temperature at the rear end of the inclosing chamber may be high or low as desired. It will be readily understood that by the arrangement disclosed, I can regulate the temperature along the chamber 2 for varying conditions.

Having thus described my invention, I claim:

- 16 1. A tunnel oven of the type described, comprising an inclosing chamber, a combustion chamber arranged longitudinally on each side of the inclosing chamber, and adapted to heat by radiation and discharge 15 the products of combustion exterior to the inclosing chamber, means for heating the combustion chamber, and means for regulating the heating means.
- 20 2. A tunnel oven of the type described, comprising an inclosing chamber, a combustion chamber arranged longitudinally on each side of the inclosing chamber, and adapted to heat by radiation and discharge 25 the products of combustion exterior to the inclosing chamber, means for heating the combustion chamber situated at one end thereof, means for heating the combustion chamber situated at sections of the length thereof, and means for conveying the products 30 of combustion from the combustion chambers.
- 35 3. A tunnel oven of the type described, comprising an inclosing chamber, a combustion chamber arranged longitudinally along the floor at each side of the inclosing chamber and adapted to heat by radiation and discharge 40 the products of combustion exterior to the inclosing chamber, means for heating the combustion chamber situated at one end thereof, means for heating the combustion chamber situated at a distance from each other and along the length of said chamber, and means for conveying the products 45 of combustion from the combustion chamber.
- 50 4. A tunnel oven of the type described, comprising an inclosing chamber, a combustion chamber arranged longitudinally on each side of the inclosing chamber and adapted to heat by radiation and discharge 55 the products of combustion exterior to the inclosing chamber, said combustion chamber consisting of a series of sections and a series of interposed sleeves, means for heating the combustion chamber located along the length thereof, and means for controlling the supply of heat.
- 60 5. A tunnel oven of the type described, comprising an inclosing chamber, a combustion chamber arranged longitudinally on each side of the inclosing chamber and adapted to heat by radiation and discharge 65 the products of combustion exterior to the

inclosing chamber, means for heating the combustion chamber situated at one end thereof, means consisting of gas and air burners arranged at intervals along said combustion chamber, and means for controlling the heat at the gas and air burners.

6. A tunnel oven of the type described, comprising an inclosing chamber, a combustion chamber arranged longitudinally on each side of the inclosing chamber and adapted to heat by radiation and discharge the products of combustion exterior to the inclosing chamber, a series of tubes arranged in the walls of the inclosing chamber and communicating with the combustion chamber, a series of gas and air burners situated in said tubes, a gas supply pipe, means for regulating the supply of gas, means for regulating the supply of air to said burners, and an exhaust flue from said combustion chamber.

7. A tunnel oven of the type described, comprising an inclosing chamber, a combustion chamber formed of a series of communicating sections arranged longitudinally on each side of the inclosing chamber and adapted to heat by radiation and discharge the products of combustion exterior to the inclosing chamber, a series of tubes extending through the walls of the inclosing chamber and communicating with each section of the combustion chamber, gas and air burners extending into each of said tubes, means for feeding gas and air to said burners, means for regulating the gas and air fed to the burners, a source of gas supply, and means for conveying the products of combustion from the combustion chamber.

8. A tunnel oven of the type described, comprising an inclosing chamber, a combustion chamber arranged longitudinally on each side of the inclosing chamber and adapted to heat by radiation and discharge the products of combustion exterior to the inclosing chamber, each combustion chamber consisting of a series of sections, a series of sleeves within which the sections may expand and contract, a series of tubes communicating with the sections within which said tubes may expand and contract, and a series of sleeves arranged external to the chamber walls and inclosing the outer ends of said tubes, gas burners located in said tubes, means for supplying gas and air to said burners, and means for conveying the products of combustion from the combustion chambers.

In testimony whereof, I affix my signature, in the presence of two witnesses.

CONRAD DRESSLER.
